UNITED STATES PATENT OFFICE.

JOSEPH F. RAUS, OF NEW YORK, N. Y.

PLASTERING MACHINE.

Application filed February 24, 1926. Serial No. 90,418.

The present invention is concerned with the provision of a machine for applying a coat of material in a plastic condition to walls, ceilings, or other flat surfaces, and 5 finds its preferred embodiment in a plastering machine.

An object of the invention is to provide a machine of this character with which coats of plaster of uniform, predetermined thickness 10 may be evenly applied to the walls or ceiling of a room.

Preferably the machine of the present invention includes a travelling carriage mounted for movement along a track. The 15 track in turn is adjustably mounted relative to a substantial base frame, so that the track may be shifted into proper position relative to a wall or ceiling surface, and then the carriage shifted along the track to effect 20 plastering of said surface. The carriage includes a plaster reservoir and a reservoir for a lubricant, such as water, and means is provided for feeding the plaster and lubricant on to the surface of the wall and 25 smoothing them down with a trowel.

It is highly desirable for the efficient operation of the machine, that the means for feeding the plaster be synchronized with the means for driving the carriage along 30 the track, so that the plaster will be applied with uniformity as the carriage is shifted along the track. By synchronizing the feeding means and the carriage driving means, the exact speed with which the carriage 35 is driven becomes relatively unimportant, since the feed of the material will be slowed down or sped up, in accordance with the speed of the carriage, and a uniform coating of plaster will be applied at all 40 times.

Preferably the plaster applying means is arranged to deliver and apply plaster to a relatively wide swathe of wall or ceiling surface, so that by the time the carriage has 45 moved from one side of a ceiling to the other, a strip of plaster of considerable width will have been applied.

In this connection it is to be noted that the main frame upon which the track is adjustably mounted is itself set in suitable 50 guide members constituting a track disposed at right angles to the carriage track. These guide members are trued up so that they are parallel to the surface being operated 55 upon. Thus, when the main frame is shifted on its tracks to permit the plaster-

ing of a new strip or section of wall or ceiling, the carriage will be spaced exactly the same distance from the surface operated upon as it was during the preceding operation. In this manner the entire surface of the wall or ceiling will be evenly coated with plaster, and the unevenness incidental to the operation of hand plastering machines will be eliminated.

Preferably also the main frame which adjustably supports the carriage rail is so constructed that it may conveniently support the carriage in position for operating on either a vertical surface or a horizontal surface. In other words, walls and ceilings 60 may be plastered with equal facility by the simple expedient of properly emplacing the main frame and adjusting the carriage guide track relative thereto.

The machine in its preferred embodiment also includes numerous refinements, such for instance as means for regulating the depth of the plaster coating which it applies, means for selectively changing the speed 70 ratios of the carriage driving means, and material feeding means, and means for protecting the working parts of the machine from falling plaster and scratcher means which is detachably mounted on the carriage 75 and may be used to scratch the first coats of plaster, and removed when the finishing coats are applied.

Further objects of the invention are to provide a machine of this character which 80 will be of simple practical construction, which will be rugged, durable and efficient in use, which may be conveniently manipulated, which will effect a material economy of time 85 and labor in a plastering operation, and which may be manufactured at a reasonable 90 cost.

With the above noted and other objects in view, the invention consists in certain novel features of construction and combinations 100 and arrangements of parts, as will be more fully hereinafter set forth and pointed out in the claims. The invention may be more fully understood from the following description in connection with the accompanying drawings, wherein—

One form of the invention is illustrated in the accompanying drawing, in which—

Fig. 1 is a side view of the entire machine 105 while in operation;

Fig. 2 a front view and

Fig. 3 a plan view of the same;

Fig. 4 a horizontal section of one end of the supporting frame;

Fig. 5 a transverse section of the plaster and water container showing the arrangement of the plaster and water compartments with their pistons and combined mechanism;

Fig. 6 a front view of the same with the lower part of the casing removed to show the piston and travel mechanisms.

10 Fig. 7 a side view of the same container with the lower end removed.

Fig. 8 a detail of the locking pins of the cover of the plaster compartment;

15 Fig. 9 a plan view of said container showing half of its top and half of its horizontal section just above the operating mechanism;

Fig. 10 a set of interchangeable gears for said mechanism;

20 Fig. 11 a partial detail of the operating mechanism; and

Fig. 12 the detail of a pawl working in combination with the rail-rack.

It is to be noted first of all that the plaster 25 and water container 1, as seen in Fig. 1, holds secured on the rail-rack 2 by means described later. It cannot fall off in whichever position the entire machine is placed but it is, nevertheless, endowed with free 30 movement along the rail-rack 2 when in operation.

It is furthermore to be noted that the supporting frame 3, seen in the same Fig. 1, and with it the whole machine, is reversible.

35 That is, it can be placed either horizontally or vertically, according to whether a ceiling or a wall is to be plastered.

When a ceiling is to be plastered, the frame 3 is placed horizontally as shown in 40 Fig. 1. The V-shaped recess 4 of the end members 5 of the same fit snugly over the two trapezoidally-shaped timbers 6. The latter serve both as supports and guides. They are temporarily fastened on trestles 45 of suitable height and laid true and level with reference to the work to be done. The frame, and with it the entire machine, is then slid along between the said guides at each new course of plaster, and the entire 50 ceiling surface to be covered is, therefore, plastered in perfect alinement. In this case two wooden saddles 7, seen in the same Fig. 1 and also in Fig. 3, are placed over the guides 6 and a plank 8 laid over them to 55 serve as a platform for the operator.

When a wall is to be plastered the frame 3, and with it the entire machine, is reversed; that is, it is made to stand on one of its ends directly on the floor. One of the trapezoidally-shaped guides 6 then is laid as 60 shown in Fig. 1, and the other either in 9 or 10, as shown in dotted lines in the same figure, according to which end of the frame is made to rest on the floor.

65 The two guides 6 are then levelled and

aligned with reference to the wall and temporarily fastened on the floor, thereby locking the member 5 of the frame end between them, but the latter is obviously free to be slid between them at each new course of plaster. The locking device just described will prevent the said frame and the rest of the machine from falling over in any direction. Thus with the machine secured between the two locking guides the entire surface of a wall is plastered in perfect plumb and alignment. In this case the operator in order to reach the full height of the wall will have to use a step ladder which may even rest on the supporting frame itself.

70 The supporting frame, to be easily carried, is made detachable. As shown in Fig. 1, it consists first of two sides each made up of two longitudinal members 12 of convenient length nailed permanently to two transverse members 13 and one brace 14.

75 The two sides hold enclosed between them at each end an inner sliding frame 15, and are held together by means of the cross members 5, 16, 17 and 18, which are fastened on them by means of the removable bolts 19, 20 and 21, thus forming a whole rigid structure. Each of the two inner frames 15 is made to slide in or out by means of the adjusting screw 22 to which the handwheel 23 is fixed, both made of steel. The screw 80 is pivoted into the two bearings 24 fixed in frame 15 and runs through the tapped anchor 25, as shown in Figs. 2 and 4. The latter is held firmly on the fixed member 18 by the bolts 26, consequently by turning the handwheel 23 the frame 15 is made to move in or out, thus bringing the attached rail-rack 2 and the container 1 it carries to the proper working line.

85 The rail-rack 2 consists of a wooden beam 27 stiffened at the bottom and top by the two pairs of steel angles 28 and 29, which are secured to the beam by the screws 30. Between the two top angles 29 the steel rack 31 is imbedded and fastened to them by the screws 32. The bolts 33 hold the rail-rack firmly secured to the sliding frames 15. The plaster and water container it carries may be slid on it from either end, or likewise 90 taken out and reversed at any time.

95 The plaster and water container 1 is made up of a steel plate casing surmounted by a cast top, all welded throughout. As seen in Fig. 5, it has one large compartment 34 for the plaster, and extending over the whole back of it one relatively small compartment 35 for the water. Each compartment has its own piston 36 and 37, respectively, for pushing plaster and water through their outlets. They work simultaneously as their rods 38 and 39 are connected at the bottom by the two arms 40. The rods 38, fixed into the plaster piston, are square-threaded screws. They mesh into the tapped holes of 100

105

115

120

125

the helical gears 41 and are forced to move up or down when said gears are made to revolve in their sockets by the driving helical gears 42, mounted on the shaft 43, which 5 is driven by hand by means of the crank-handle 44. As the shaft 43 extends out of the casing on both sides, as shown in Fig. 6, the crank-handle may be removed from one side and placed on the other, according to 10 what the case may require.

Actuated from the same crank-handle 44 and shaft 43 is the rack pinion 45 by means of the transmission gears 46, 47 and 48, as shown in Figs. 6, 7, 9 and 11. In Fig. 9 it is 15 clearly seen that the driving motion of the crank-handle is first transmitted through the inner gears 46 to the outer gear 47, and in turn the gear 47 drives the gear 48 which is mounted on the square-sleeved terminal of 20 the shaft 49 of the said pinion 45. The purpose of this arrangement is, first, to allow the rack pinion 45 to be disconnected at any time from the motion of the crank-handle by pulling out the gear 48, as shown in Fig. 25 11, and so let the two pistons alone work and push up plaster and water to their outlets after a new charge of these materials has been made, without disturbing the container from its position; second, to allow the two 30 gears 47 and 48 to be interchanged with any of the two differential combinations of gears 50 and 51, shown in Fig. 10.

By the latter arrangement, for every turn of the crank-handle the rack pinion 45 will 35 make one turn when gears 47 and 48, of equal diameters, are in place, as shown in Figs. 7 and 9; one and one half turn and two turns, respectively, when either combination of gears 50 or 51 of Fig. 10 is substituted for them. The travel of the container 40 1 along the rail-rack 2, consequently, will be directly proportional to the turns of pinion 45, and for this reason the same amount of plaster will be distributed over surfaces extending in the proportion of 1 to 1, 1½ to 1, 45 applying as a result three different coats of plaster, that is, thick, medium, and thin, respectively. The interchangeable gears are held in place by the removable cotter pins 52, and a cover plate 53 is slid down over 50 them both as a protection from falling plaster and a stop to hold in place gear 48 or its substitute.

A pawl 54 engaging into the teeth of the 55 rack 31 and mounted on the shaft 55, shown in Figs. 5, 9, and 12, with said shaft extending out of both sides of the casing, as seen in Fig. 6, and with two torsional springs 56, is provided to hold in place the container 60 1 at any height when walls are to be plastered and the frame 3 with the rail-rack 2 are, therefore, in vertical position. In Fig. 12 (a) and (b) show the position of the pawl with respect to the rack when the container 65 1 is at rest and when in motion, re-

spectively. Said pawl may at any time be disconnected from the rack 31 by turning outwardly the handle 57, which fits either end of the shaft 55, and pressing down its pin 58, thereby locking it on the side of the 70 container 1, as shown in dotted lines in Figs. 7 and 9. In Fig. 5 also may be seen in dotted lines the position of the said pawl when disconnected from the rack.

Mounted on the shafts 43 and 49 are also 75 two pairs of rollers 59 and 60, which together with the two angles 61 riveted to inner extensions of the casing plate keep the container 1 locked on the rail-rack 2, by holding between them the flanges of the two 80 angles 29, at same time endowing said container with free movement along the said rail-rack.

The whole mechanism of shafts, gears and 85 pawl is mounted into the steel frame 62 which is fixed into the container casing by means of the outer screws 63, seen in Figs. 1, 2 and 7. The casing extends beyond the frame 62 down to almost the bottom line of the rail-rack 2, first to protect the piston 90 rods; second, to counteract in part the unbalanced weight of the container itself when the machine is placed vertically. Weights may be placed to this effect in its vacant space if necessary. 95

On top of the plaster compartment is the long and narrow outlet 64, and next to it fastened into a groove is the trowel 65. This has the two rounded edges visible in Figs. 1, 5 and 7, and a slit 66 in its middle, 100 shown in Figs. 3 and 9, extending from end to end, which connects into the internal holes 67, and through these into the water compartment, as shown in Fig. 5. When the machine is in operation the plaster is gradually squeezed out through the outlet 64 by the piston 36, and the trowel 65 that follows presses and smooths it against the wall or ceiling. Water from its compartment is at the same time forced by the piston 37 110 through the slit 66 between the trowel and the plaster, and acts as a lubricant preventing the plaster from adhering to the trowel. 115

Placed behind the trowel and fastened into a groove is the scratcher 68, in order to automatically scratch the scratch coats of plaster, but it is removed when the brown and finish coats are to be applied, and a blank is placed into its groove to prevent falling plaster collecting into it. Both the trowel and the scratcher are held in their grooves by the locks 69 and 70, respectively, which are turned to one side, as shown in dotted lines in Fig. 7, when either one is to be pulled out. 120

In order to refill the plaster compartment the cover 71 is removed from the casing by turning outwardly the hinged pins 72 and 73, as shown in dotted lines in Fig. 8, which keep it locked on the two fan-like projections of the outlet 64. In order to refill the 125 130

water compartment the cover plate 74 of the hood 75 is simply slid off its watertight grooves shown in both Figs. 5 and 7.

Having thus described the details of my invention, I claim:

1. In a plastering machine, the combination with a supporting frame and a track adjustably carried thereby, of a carriage on the track, a plaster compartment in the carriage, a trowel mounted adjacent the outlet end of said compartment for smoothing the plaster delivered therefrom, means for propelling the carriage along the track, a follower piston for extruding plaster from the compartment, a common drive for said propelling and feeding means, and means for selectively uncoupling the propelling means from the drive, whereby when the plaster compartment is reloaded, the piston may force the plaster to the outlet opening without movement of the carriage on the track.
2. In a plastering machine, the combination with a supporting frame and a track adjustably carried thereby, of a carriage on the track, a plaster compartment in the carriage, a trowel mounted adjacent the outlet end of said compartment for smoothing the plaster delivered therefrom, a lubricant compartment in the carriage, means for delivering lubricant to the trowel, and means for extruding plaster from the outlet opening.
3. In a plastering machine, the combination with a supporting frame and a track adjustably carried thereby, of a carriage on the track, a plaster compartment in the carriage, a trowel mounted adjacent the outlet end of said compartment for smoothing the plaster delivered therefrom, a lubricant compartment in the carriage, means for delivering lubricant to the trowel, and means for extruding plaster from the outlet opening, said lubricant feeding and plaster extruding means being connected together for simultaneous movement.
4. In a plastering machine, the combination with a supporting frame and a track adjustably carried thereby, of a carriage on the track, a plaster compartment in the carriage, a trowel mounted adjacent the outlet end of said compartment for smoothing the plaster delivered therefrom, a lubricant compartment in the carriage, means for delivering lubricant to the trowel, and means for extruding plaster from the outlet opening, said lubricant feeding and plaster extruding means being connected together for simultaneous movement, said feeding and extruding means comprising a pair of pistons and a bar rigidly connecting the pistons.
5. In a plastering machine, the combination with a supporting frame and a track adjustably carried thereby, of a carriage on the track, a plaster compartment in the carriage, a trowel mounted adjacent the outlet

end of said compartment for smoothing the plaster delivered therefrom, a lubricant compartment in the carriage, means for delivering lubricant to the trowel, means for extruding plaster from the outlet opening, a drive shaft from which the feeding and extruding means are actuated, and carriage propelling means driven from said drive shaft.

6. A device as set forth in claim 2 and wherein the outlet opening for the lubricant is through the body of the trowel.

7. A device as set forth in claim 2, and wherein supporting means for a removable scratcher is mounted on the carriage behind the trowel.

8. In a plastering machine, a track and a travelling carriage overhanging the track at opposite sides, plaster and water compartments in the carriage, pistons for forcing the plaster and water from the compartments, and a trowel associated with the water outlet for smoothing the plaster.

9. In a plastering machine, a track and a travelling carriage overhanging the track at opposite sides, plaster and water compartments in the carriage, pistons for forcing the plaster and water from the compartments, a trowel associated with the water outlet for smoothing the plaster, and piston rods for the pistons mounted in the overhung portions of the carriage to balance the latter.

10. In a plastering machine, a track and a travelling carriage overhanging the track at opposite sides, plaster and water compartments in the carriage, pistons for forcing the plaster and water from the compartments, and a trowel associated with the water outlet for smoothing the plaster, said track including a rack toothed portion, a gear on the carriage meshing with the rack, and a pawl for locking the carriage against retrograde gravitational movement on the track.

11. In a plastering machine, a track and a travelling carriage overhanging the track at opposite sides, plaster and water compartments in the carriage, pistons for forcing the plaster and water from the compartments, and a trowel associated with the water outlet for smoothing the plaster, said track including a rack toothed portion, a gear on the carriage meshing with the rack, a pawl for locking the carriage against retrograde gravitational movement on the track, and means for selectively rendering the pawl inoperative.

12. In a plastering machine, a guide track adapted to be disposed in parallelism with the surface to be plastered, a main frame shiftable along the track, a plaster carriage track on the main frame disposed at right angles to the main frame track, a plaster

carriage movable along said carriage track, and means for adjusting the plaster carriage track relatively to the main frame track.

13. In a plastering machine, a track adapted to be disposed in parallel relation to the surface being plastered, a main frame shiftable along the track, a plaster carriage track adjustably supported on the main frame and disposed at right angles to the main frame track, means carried by both sides of the main frame for interfitting with the track, whereby the main frame when laid on either side may be shifted along the track, said means cooperatively interfitting with the track when the main frame is disposed in vertical position, whereby the main frame

may be shifted along the track while in vertical position, and whereby the plaster carriage track may consequently be disposed in either horizontal or vertical position to 20 plaster both walls and ceiling.

14. A device of the class described in claim 13 and including means for positively interlocking the main frame track with the main frame to prevent tilting when the main frame is in position to dispose the carriage track in a vertical plane. 25

Signed at New York city in the county of Bronx and State of New York this twenty-tieth day of February A. D. 1926.

JOSEPH F. RAUS.
